ERNEST R. VIBERG, OF MONTREAL, QUEBEC, CANADA

JOURNAL BOX LID ASSEMBLY

Application filed April 6, 1931. Serial No. 527,902.

This invention relates to journal boxes and comprises certain improvements in the construction and mounting of the journal box lid and the spring provided for holding the lid in open or closed position.

A particular object of the invention is to provide improved means for releasably holding in place the hinge pindle connecting the lid to the journal box, said means permitting the pindle to be readily freed for removal by a simple movement of the lid after the spring pressure exerted on the lid has been released.

Another object is to provide a lid having a continuous marginal flange fitting over the mouth portion of the journal box to prevent entrance of dirt and dust between the lid and the body portion of the box.

Another object is to provide a rugged and economical lid construction in which the dust excluding flange, the pindle receiving sleeves and the spring supporting and retaining means are all cast integral with the body portion of the lid.

A further object is to provide a generally improved and simplified lid and spring assembly in which the spring is held to the lid by parts cast integral with the body portion of the lid.

Other objects and advantages of the invention will be more readily understood from the following detailed description and accompanying drawings, wherein—

Figure 1 is a perspective view of a journal box equipped with a lid and spring assembly constructed in accordance with this invention. In this view the lid is shown in closed position.

Figure 2 is a view similar to Figure 1 but showing the lid in open position.

Figure 3 is a front view of the lid and spring assembly detached from the journal box.

Figure 4 is a side view of the assembly shown in Figure 3.

Figure 5 is a fragmentary vertical sectional view taken substantially along the line 5—5 of Figure 1.

Figure 6 is a view similar to Figure 5 but showing the lid in open position.

Figure 7 is a fragmentary end view of the

lid showing the manner in which the bore of one of the pindle receiving slots is partially closed at its outer end.

Referring more particularly to the drawings 11 designates a journal box provided with the usual mouth opening 12 and pindle lug 13. The lid 14 is cast with a continuous inwardly projecting marginal flange 15 adapted to fit over the wall 16 surrounding the mouth opening 12 in order to prevent the entrance of dust or dirt. A U-shaped rib 17 is formed to project inwardly from the lid in spaced relation to the flange 15 and serves as an oil deflector, as is well known in this art. Pindle sleeves 18 and 18' are cast integral with the body of the lid and the upper portion of the flange 15 to receive the ends of the hinge pindle 19 passing loosely through the lug 13. The lug 13 is provided with the usual angularly related flat cam faces 13a and 13b adapted to co-operate with a spring carried roller 20 to hold the lid in either open or closed position. The roller carrying spring consists of two coils 21 and 22 connected by an intermediate U-shaped portion 23 which is formed as an integral continuation of the inner terminal convolutions of the coils and carries the roller 20. The outer convolutions of the coils 21 and 22 are extended downwardly along the outer face of the lid to provide a pair of parallel side arms 24 having their lower ends received in vertical sockets 25 cast integral with the outer face of the lid. The coils 21 and 22 bear against the inner surface of a transversely curved fulcrum or retaining member 26 which extends across the upper central portion of the lid and has its ends integrally joined thereto by means of the parallel side walls or webs 27. The lower portions of these webs 27 form the outer side walls of the sockets 25 while the upper portions of said webs are merged with the inner ends of the pindle sleeves 18 and 18'. The outer face of the lid may also be formed with a U-shaped strengthening rib 27 presenting a horizontal portion 28 positioned adjacent the lower edge of the lid and vertical portions 29 extending upwardly in spaced relation to the side edges of the lid.

and merging with outer end portions of the pintle sleeves. When the lid is in the closed portion shown in Figure 5 the engagement obtaining between the roller 20 and the cam

- 5 face 13a of the lug 13 causes the parallel arms 24 of the spring to exert pressure against the central portion of the cover to hold the cover firmly against the contacting faces of the journal box. When the lid is 10 raised to the open position shown in Figure 6 the roller 20 rides over the cam face 13a of the lug 13 and onto the cam face 13b so that in this position of the roller with reference to the lug 13 the spring becomes effective to retain the lid in its open position.

When the parts are assembled as shown in Figures 1 and 2 the hinge pintle is held in place by a particular formation of the pintle sleeves 18 and 18' which will now be 20 described. As shown to advantage in Figures 4 to 6 inclusive each sleeve is provided with a pintle receiving bore 18a which is generally elliptical or oval in cross section being formed with the axis A longer than 25 the axis B. These bores extend through to the inner surfaces of the pintle sleeves but are partially blocked at their outer ends. In the case of the sleeve 18 the outer end of the bore is partially blocked by a continuous 30 pintle engaging flange or ledge 30 leaving a relatively small opening 31 for the insertion of a tool for the purpose of removing the pintle, as hereinafter described. The outer end of the bore formed in the sleeve 35 18' is partially blocked by a crescent shaped ledge or flange 32 which leaves a circular opening 33 for the insertion of the pintle.

In applying the lid a suitable tool is engaged beneath the roller 20 to press same in 40 the direction of the spring retaining or fulcrum member 26 in order to permit the bores of the sleeves 18 to be aligned with the pintle receiving opening of the lug 13. The pintle 19 is then passed through the circular opening 33 of the sleeve 18' so that the ends of the pintle are seated in the sleeve bores with the central portion of the pintle passing 45 through the lug 13. The length of the pintle is such that when one end is engaged with the flange or ledge 30 of the sleeve 18 the other end lies inwardly of the crescent shaped flange or ledge 32 of the sleeve 18'. The elliptical or oval shape of the sleeve bores provides sufficient clearance to permit the 50 sleeves to be moved laterally with reference to the pintle by the pressure of the spring roller 20 when this roller is released to bear against the lug 13. This lateral movement of the sleeves causes the crescent shaped ledge or flange 32 to move opposite the adjacent end of the pintle to form a stop preventing outward movement of the opposite end of the pintle with reference to the sleeve 18'. Outward 55 movement of the opposite end of the pintle with reference to the sleeve 18 is prevented

by the continuous flange or ledge 30. When the pintle is to be removed the pressure of the spring roller against the lug 13 is released to permit the sleeves to be shifted to a position bringing the circular opening 33 of the sleeve 18' opposite the adjacent end of the pintle so that the pintle can be driven outwardly through this opening by means of a tool inserted through the opening 31 of the sleeve 18.

Another advantage of the lid and spring assembly described in the foregoing is that the spring retaining or fulcrum member 26 extends over the upper portion of the coils 21 and 22 a sufficient distance to hold the spring arms 24 against accidental escape from the sockets 25. It will thus be seen that the lid and spring assembly as described herein may be shipped to the point of use without any danger of accidental separation and may be applied to the journal box or removed therefrom as a unit.

Having thus described my invention, what I claim is:

1. A journal box lid and spring assembly comprising a lid provided with laterally spaced webs projecting from the outer surface of the lid, a transversely curved wall member extending between the webs and rigidly connected thereto, said wall member having its curved surface facing inwardly to form a cavity spaced from the opposing outer surface of the lid, a spring presenting spaced coils seated in said cavity, a U-shaped portion connecting the inner convolutions of the coils and projecting beyond the upper edge of the lid, a roller carried by said U-shaped portion, a pair of side arms formed integral with the outer convolutions of the coils and extending towards the lower edge of the lid, sockets formed on the outer face of the lid and receiving the lower ends of said arms, and pintle receiving sleeves carried by the upper edge of the lid and disposed at opposite sides of said roller in spaced relation thereto.

2. A journal box provided with a pintle lug, a lid provided with pintle receiving sleeves lying at opposite sides of said lug, a pintle passing through the lug and having its end portions fitted in said sleeves, vertically extending webs projecting from the outer surface of the lid in relatively spaced relation, a wall member extending between the webs and rigidly connected thereto, said wall member having its inner surface transversely curved and spaced from the opposing outer surface of the lid, sockets cast integral with the lower portions of the webs and the outer surface of the lid, a spring presenting spaced coils seated in the cavity formed by the transversely curved inner surface of said wall member, a U-shaped portion formed as a continuation of the inner convolutions of the spring coils and pro-

jecting beyond the upper edge of the lid, a
roller carried by said U-shaped portion in
riding engagement with the pintle lug, a
pair of side arms constituting downward ex-
5 tensions of the outer convolutions of the
spring coils and having their lower ends re-
ceived in said sockets.

In witness whereof, I have hereunto set my
hand.

ERNEST R. VIBERG.
